H. W. O'NEILL

SWITCHING DEVICE

Filed Oct. 30, 1922

Inventor:
Henry W. O'Neill,
by W. E. Beatty, Atty.

UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

SWITCHING DEVICE.

Application filed October 30, 1922. Serial No. 597,765.

To all whom it may concern:

Be it known that I, HENRY W. O'NEILL, a citizen of the United States, residing at Brooklyn, in the county of Kings, State of New York, have invented certain new and useful Improvements in Switching Devices, of which the following is a full, clear, concise, and exact description.

This invention relates to switching devices 10 and more particularly to circuit controlling devices responsive to both alternating current and direct current.

In employing direct currents as the transmission agent in signaling over line circuits 15 possessing high reactance, it is well known that distortion of impulses takes place, and as the rate or signaling speed is increased the impulses soon become mutilated to the extent that either false signals will result or 20 entire failure of translation may obtain at a receiving station or at a repeating point. Therefore, with direct currents dependable operation may, in general, be had only when the signaling speed is relatively low. On 25 the other hand, it is a phenomenon of alternating currents that little or no distortion of signaling impulses will be had under conditions where direct current impulses may prove entirely inadequate. In communication work, particularly with regard to telephone circuits, it is necessary to avoid the 30 use of derived or bridged paths of low impedance on the main conductors of a circuit in order that transmission losses will be reduced to a minimum. As well understood, 35 the joint impedance of two reactive paths in parallel, falls approximately in the ratio of 1 to 4 as compared with a single path, therefore, advantage will lie with a system in 40 which the number of bridged paths may be a minimum, while the impedance of each path will be high.

To the end that the foregoing conditions 45 may be met, the present invention contemplates a relay unit of universal type relative to control by direct currents, alternating currents, or combinations of such currents in so-called superposed form. In this device, 50 the control coil or winding presents a single path of high impedance when joined in bridge on the main conductors of a telephone circuit, from which direct currents corresponding with certain slow speed signaling 55 effects may energize a magnetic circuit to cause an associated armature to effect con-

trol of local or secondary circuits. In turn, 60 alternating currents in the form of high speed signaling impulses may traverse this winding and act through the same magnetic paths in influencing the armature to independently control other local or secondary circuits.

The device to be described and claimed 65 hereinafter is particularly adaptable for use in telephony and telegraphy and has a more particular adaptation to machine switching systems wherein magnetic devices of this nature are subjected not only to direct current and alternating current but also to superimposed currents caused to flow by the manipulation of suitable sending devices.

The invention will be readily understood 70 from the following detailed description, reference being had to the accompanying drawing which shows a schematic view of 75 the relay structure and a simple circuit arrangement wherein such relay has particular use.

The relay comprises a permanent magnet 80 50 and a soft iron frame 51 which serves as a magnetic path for the flux set up by a winding 52 in magnetizing a reed armature 14 having a loose circuit controlling element 22 insulatively mounted thereon. The circuit controlling element 22 may be of any of 85 the types disclosed in a copending application of Henry W. O'Neill, Serial No. 558,491, filed May 4, 1922, and comprises a sealed tubular shaped receptacle 53, preferably of glass, having leading-in terminals 54, 54 to which the terminals of any local 90 circuit may be connected. A loosely suspended inertia metallic member 55 is contained in the receptacle 53 and serves as a contacting means for the leading-in terminals 54, 54. The member 55 may be a rod 95 provided with a cavity at each end to provide contacting surfaces and a support for the member itself.

When the reed 14 is at rest, the terminals 100 54, 54 are electrically continuous. When the reed is vibrated at a predetermined rate in response to alternating current, the contacts will be agitated to such an extent as to break the electrical continuity of the terminals 54, 54.

The reed armature 14 is resiliently mounted 105 on the base portion of the core 51 and forms a conducting link in the electrical circuit disclosed. This armature has reduced 110

portions at its extremities to provide flexibility.

The following description will be directed to the operation of the circuit shown in the drawing.

The relay 10 is shown bridged across a pair of line conductors 11 and 12 which may constitute a telephone line. Bridged across the same line is a line relay 13 which is 10 adapted to be energized upon the initial actuation of relay 10 and thereafter to follow the vibrations of the reed armature 14 which is caused to vibrate by impulses sent out by the dial switch 15.

15 Assuming the dial switch 15 to be unoperated, the key 16 is closed in order to seize the switching apparatus associated with line relay 13, whereupon a circuit is established for relay 10 extending from the positive 20 pole battery 17, line conductor 11, winding of relay 10, line conductor 12, to the negative pole of battery 17. Relay 10 thereupon energizes and attracts its armature 14 closing the contacts 20, thereupon establishing 25 a circuit for line relay 13 which may be traced from grounded battery, right-hand winding of relay 13, conductor 18, impedance coil 19, stationary conducting terminal 30, through the stop 56, contact 20, armature 14, conductor 21 through the circuit controlling element 22, conductors 23 and 24, and thence to ground through the lefthand winding of relay 13. Relay 13 thereupon energizes and attracts its armature to 35 control the operation of any device such as a stepping switch which may be associated therewith.

The dial 15 which is associated with the alternating current supply 25 is now operated. The functioning of such dials is well known to those skilled in the art and no detailed description thereof is deemed necessary here, but it may be said that when the dial finger plate is rotated from normal to 40 an identified notch and then released, the dial mechanism returns to normal under the action of a spring, and in so doing, actuates a pair of contact springs 31 to intermittently supply current from alternating current 45 source 25 in accordance with the number dialed. Assuming the number 9 has been dialed, nine current impulses will be sent out through the winding of relay 10, causing the reed 14 to vibrate (the contact 20 remaining closed all the while). For each 50 vibration of the reed the energizing circuit for relay 13 is interrupted at the contacts of the circuit controlling element 22 so that the armature of relay 13 oscillates in accordance with the impulses sent out by the 55 dial 15. Should this armature control the operation of a stepping switch the switch would be advanced nine steps in accordance with the manipulation of the dial 15.

60 The impedance coil 19 is included in the

contact circuit in order to prevent short circuiting the alternating current, such as voice current, which may flow over the line. The condensers 40 and 41 are included in the line circuit, as shown, to prevent the current 70 from battery 17 flowing out over the line and operating relay 13 without the inclusion in the circuit of the circuit controlling element 22.

The inertia of the armature 14 is relatively 75 great and although it may readily respond to direct current effects with sufficient amplitude to change its position with respect to the stops 56, 56, the relatively high frequency currents, although adequate to set up 80 vibrations whereby the inertia member 55 may be sufficiently accelerated to control the circuit therethrough, these high frequency currents are not, however, capable of effecting an amplitude of armature 14 to cause 85 it to change position with respect to the stops.

In the structure of this relay, maximum efficiency is obtained with respect to the control of the armature, whether under control 90 of alternating current or direct current, since the magnetic structure, as a whole, is shared alike by the fluxes produced by both currents.

What is claimed is:

1. In a relay structure, an operating winding, an armature therefor, a plurality of contacts associated with said armature, one of said contacts being operated upon application of direct current to said winding, 100 and another contact being operated upon application of alternating current to said winding.

2. In a relay structure, an operating winding, an armature therefor, normally made 105 contacts associated with said armature, and other contacts associated with said armature, said last contacts being made upon application of direct current to said winding, and said first contacts being intermittently 110 broken when alternating current is applied to said winding.

3. In a relay structure, an operating winding responsive to superimposed currents of different characteristics, an armature therefor, a circuit controlling element mounted on said armature, and a contact, said contact adapted to be operated upon application of one current to said winding, and said circuit controlling element adapted to 115 be operated upon the superimposition of a second current on said winding, said contact being maintained operated during the operation of said circuit controlling element.

4. In a switching device, an operating winding, an armature therefor forming a part of an external electrical circuit, and means associated with said armature for completing the aforesaid electrical circuit upon application of direct current to said 125 130

operating winding, and for intermittently tact points associated with said armature opening said circuit upon application of and adapted to be operated responsive to 10 alternating current to said winding.

5. In a relay, a permanent magnet, an

electromagnet, a reed armature, a loose contact device mounted on said armature and responsive to the energization of said electromagnet by alternating current, and con-

In witness whereof, I hereunto subscribe my name this 24th day of October A. D. 1922.

HENRY W. O'NEILL.
